Atty.

UNITED STATES PATENT OFFICE.

THOMAS CORSCADEN, OF NEW BRITAIN, CONNECTICUT, ASSIGNOR TO THE STANLEY WORKS, OF SAME PLACE.

MANUFACTURE OF STRAP-HINGES.

SPECIFICATION forming part of Letters Patent No. 519,243, dated May 1, 1894.

Application filed September 27, 1893. Serial No. 486,616. (No model.)

To all whom it may concern:

Be it known that I, THOMAS CORSCADEN, a citizen of the United States, residing at New Britain, in the county of Hartford and State 5 of Connecticut, have invented certain new and useful Improvements in the Manufacture of Strap-Hinges, of which the following is a specification.

My invention relates to improvements in 10 the manufacture of strap hinges, and the object of my improvement is to make a symmetrical hinge without any waste of stock.

In the accompanying drawings: Figure 1 is a plan view of one of my hinge blanks together with portions of other blanks, the 15 same illustrating the method of cutting said blanks from a bar or plate of metal. Fig. 2 represents in plan view one of the blanks shown in Fig. 1 as having been subjected to 20 the second step in my process.

In my prior patent, No. 476,521, dated June 7, 1892, I described and claimed the same method of cutting the first blanks from a bar of metal, but I utilized those blanks in the 25 form in which they were thus cut.

In my present improvement, I first cut the blanks as described in said patent and shown in Fig. 1 of the accompanying drawings, and then I bend these blanks edgewise to throw 30 them from the form of blank shown at A in Fig. 1 into the form of blank which is shown in Fig. 2. The blank, Fig. 2, is long enough for forming a pair of hinge leaves for a strap hinge, said blank being divided at the knuckle 35 portion as indicated by broken lines in said Fig. 2, after which the knuckles are rolled and the hinge finished in the ordinary manner.

In cutting the first blanks A, Fig. 1, I take a bar or plate of metal wide enough for cutting two rows of blanks and cut them on the 40 dividing lines shown, so that the widest part of one blank is cut from the narrower part of the adjacent blank with the longest line of division between them extending obliquely to the length of the bar of metal, while the opposite edges of these blanks are left straight and are formed by the original edge of the bar or plate of metal. It will thus be seen that there is no waste of stock in cutting the blanks A. Bending or swaging these blanks edgewise 45 from the form shown in Fig. 1 to that shown in Fig. 2 makes a symmetrical blank of proper form for making a pair of hinge leaves for a strap hinge of the ordinary lozenge shape. This second operation is inexpensive and can 50 readily be performed in suitable dies when the metal is cold.

I claim as my invention—

The herein described method of manufacturing strap hinges which consists in cutting 60 blanks for a pair of hinge leaves with each tapering leaf blank having one straight edge and one oblique edge as shown, then swaging said blanks edgewise throughout their tapering portion into a symmetrical shape with 65 two oblique edges, and subsequently forming hinges from said blanks, substantially as described and for the purpose specified.

THOS. CORSCADEN.
